ATTORNEYS

UNITED STATES PATENT OFFICE.

WENDELL P. BOSWORTH, OF BROCKTON, MASSACHUSETTS.

LINK MAT.

1,200,461.

Specification of Letters Patent.

Patented Oct. 10, 1916.

Application filed March 20, 1916. Serial No. 85,389.

To all whom it may concern:

Be it known that I, WENDELL P. BOSWORTH, a citizen of the United States, residing at Brockton, in the county of Plymouth 5 and State of Massachusetts, have invented new and useful Improvements in Link Mats, of which the following is a specification.

This invention relates to a floor mat which includes staggered links, parallel coupling rods on which the links are strung, and spacing washers strung on the rods at opposite ends of the mat to space the links forming said ends, the links and washers being preferably made from scraps or small pieces 15 of sole leather.

The object of the invention is to provide a mat of this character with a detachable panel, which may bear letters or other indicia denoting the ownership of the mat, 20 the letters being for example the initials of the owner's name, and the construction being such that either side of the mat may be the top side, of which the lettered side of the panel forms a part.

25 The invention is embodied in the improvements which I will now proceed to describe and claim.

Of the accompanying drawings forming a part of this specification: Figure 1 represents a plan view of a mat embodying my invention; Fig. 2 represents a view similar to Fig. 1, the panel being absent; Fig. 3 represents a section on line 3—3 of Fig. 1; Fig. 4 represents a perspective view of the panel 35 shown by Figs. 1 and 3; Fig. 5 represents a perspective view of a smaller panel or a panel unit.

The same reference characters indicate the same or similar parts in all the views.

40 My improved mat includes a body portion formed by stringing on a series of parallel wire rods 12 a plurality of links 13, each of which is preferably composed of a group of small strips or blanks of sole leather perforated at their end portions to receive the rods 12. The links are staggered, as shown, and the links forming the opposite ends of the mat are spaced apart by outer spacing washers 14 also strung on 45 the rods.

A mat of the general construction above described is common and well known, the links being uniformly distributed, so that the only openings in the mat are those 55 formed by the adjacent sides and ends of the links and the spacing washers.

In carrying out my invention I form, preferably in the central portion of the mat, an opening 16 of greater area than the combined area of two or more of the links. Said 60 opening, which is formed by omitting some of the links, has two opposed selvage edges, formed by inner spacing washers 14^a and the portions of the links 13 spaced thereby, this construction rendering the two opposed 65 edges permanent and free from liability to distortion. The opening 16 also has two opposed edges of angular form and presenting inwardly offset edge portions 13^a formed by the sides of some of the links 13. 70 Some of the wires 12 extend across the opening 16, and the links forming the offset portions 13^a are free to slide or be displaced on said wires when the mat is in the condition shown by Fig. 2. Said displaceable links 75 are however confined in the completed mat by the panel next described. Said panel is preferably a single block 17 of elastic material, such as rubber, or a composition containing rubber, and is formed to fill the 80 space between the offset portions 13^a at one edge of the opening and those at the opposite edge, so that when the panel is in place none of the links 13 are displaceable.

The panel is provided with means for detachably engaging the portions of the rods 12 which extend across the opening 16, said means being preferably embodied in slots 18, formed in the under side of the panel, and formed and arranged to receive said 90 rod portions. The slots are narrower than the diameter of the rods so that their sides are indented by and grip or hug the rods, as indicated by Fig. 3. The panel is therefore firmly, although detachably, engaged with 95 the mat, and is applicable to and removable therefrom in a side-wise direction.

The upper surface of the panel may be provided with a plurality of initial letters, as shown by Figs. 1 and 4, these being applied to the panel in any suitable way, and either flush therewith, as shown, or sunken or raised. The detachable connection between the panel and mat enables the mat to be used either side up, the lettered side of 105 the panel being at the top.

The panel shown by Figs. 1 and 4 is adapted to engage four rods 12, the opening 16 being formed to expose that number of rods. Should a smaller opening be desired, 110 the panel may be adapted to engage two rods, as shown by Fig. 5. The panel last

referred to may be a unit of a larger panel composed of two or more of said units placed edge to edge and each provided with a single letter.

- 5 Having described my invention, I claim:
1. A link mat comprising staggered links, parallel coupling rods passing through the said links, some of the links being omitted to form a panel-receiving opening across which some of the rods extend, and a panel inserted in said opening and bearing on links at opposite sides of said opening to prevent their displacement on the rod portions extending across said opening, said panel having means permitting its detachable engagement with said rod portions, by a sidewise movement of the panel.

2. A link mat comprising staggered links, parallel coupling rods passing through the said links, some of the links being omitted to form a panel-receiving opening across which some of the rods extend, and a panel inserted in said opening and bearing on links at opposite sides of said opening to prevent their displacement on the rod portions extending across said opening, said panel being of elastic material and having slots in its under side formed to detachably engage said rod portions, and normally narrower than the diameter of the rods, so that the sides of the slots are indented by the rods.

In testimony whereof I have affixed my signature.

WENDELL P. BOSWORTH.
